MUFFLER

Eldred G. Straw, Grass Lake, Mich., assignor to Walker Manufacturing Company, a corporation of Delaware

Filed Feb. 3, 1965, Ser. No. 83,680

Term of patent 14 years

(Cl. D14—6)

FIG. 1 is an enlarged fragmentary perspective view of a muffler showing my new design.

FIGURE 2 is a side elevational view thereof;

FIGURE 3 is another side elevational view thereof with the muffler rotated approximately 45° from the position illustrated in FIGURE 2,

FIGURE 4 is a transverse cross-sectional view taken along the line 4—4 of FIGURE 2, and

FIG. 5 is a perspective view thereof taken on a slightly smaller scale.

I claim:

The ornamental design for a muffler, substantially as shown and described.
